United States Patent Office

Des. 227,616
Patented July 3, 1973

227,616

NOZZLE FOR HAIR DRYER

Stephen K. Lauderback, Elmhurst, Ill., assignor to
Sunbeam Corporation, Chicago, Ill.

Filed Apr. 6, 1972, Ser. No. 241,863

Term of patent 14 years

Int. Cl. D28—03

U.S. Cl. D86—10 F

FIG. 1 is a perspective view of a nozzle for hair dryer embodying my new design;

FIG. 2 is a top plan view thereof;

FIG. 3 is a front elevational view thereof;

FIG. 4 is an end elevational view thereof;

FIG. 5 is a cross sectional view taken along line 5—5 of FIG. 3; and

FIG. 6 is a cross sectional view taken along line 6—6 of FIG. 3.

I claim:

The ornamental design for a nozzle for hair dryer, as shown.
